The ornamental design for an auxiliary light for vehicle having attached plowblade, as shown and described.

DESCRIPTION

FIG. 1 is a side pictorial view of an auxiliary light for vehicle having attached plowblade showing my new design;

FIG. 2 is a front elevational view thereof;

FIG. 3 is a right side elevational view thereof which is similar to the left side elevational; and,

FIG. 4 is a top plan view thereof.

The mounting elements are shown in broken lines for illustrative purposes only.
